UNITED STATES PATENT OFFICE.

WILLIAM WRIGHT, OF CHICAGO, ILLINOIS, ASSIGNOR, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed October 14, 1924. Serial No. 743,540.

This invention relates in general to improvements in freight car roofs and more particularly to improvements in the class of car roofs usually designated as "outside metal roofs", which outside metal roof is movably or flexibly positioned on the car so as to cover the wooden sheathing, or inside wooden roof of the car; and objects of the invention are the provision of a metallic roof capable of movement in harmony with weaving motion of the car without the necessity of providing mullions spaced throughout the length of the roof to prevent the outside metal roof from shifting longitudinally; the provision of anchors for such car roofs which anchors are not exposed to the elements and which are arranged to hold the sheets from upward movement and from too great longitudinal movement; the provision of a roof which is simple to manufacture at a reasonable cost and which can be readily applied without the necessity of specially skilled workmen and which when applied will be weathertight and not require frequent repair and replacement; the arrangement of the parts in such a roof so as to reduce to a minimum the number of points of contact between the parts to eliminate chafing especially at points exposed to the elements; and such other objects and advantages of the invention as may be found to obtain in the structure hereinafter set forth and claimed.

In the accompanying drawings forming a part of this specification and showing, for purposes of exemplification, a preferred form and manner in which the invention may be embodied and practiced, but without limiting the claimed invention specifically to such illustrative instance or instances:

Figure 1 is a top plan view of a car roof embodying the invention, parts being broken away for better illustration.

Fig. 2 is a side elevational view of a portion of the same.

Fig. 3 is a diagrammatic view, taken transversely of the roof, illustrating the position of the roof sheets when assembled on a car.

Fig. 4 is a vertical cross-sectional view taken on the line 4-4 of Fig. 1.

Fig. 5 is a top plan view of a portion of eaves corner of a roof sheet.

Fig. 6 is a vertical sectional view taken on the line 6-6 of Fig. 1.

Fig. 7 is a vertical cross-sectional view taken on the line 7-7 of Fig. 1.

Fig. 8 is an end elevational view taken at the eaves end of a side seam cap.

Fig. 9 is a top plan view of the same, showing the arrangement of the anchor in dotted lines.

Fig. 10 is a top plan view of one of the anchors.

Fig. 11 is an end elevational view of the same.

Fig. 12 is a side elevational view of the same.

Fig. 13 is a vertical cross-sectional view taken on the lines 13-13 of Fig. 1.

Fig. 14 is a top plan view, parts being broken away, taken over the ridge corner of the roof sheets and ridge cap.

On the drawings, 20 indicates the wooden side plates that extend longitudinally of the car and 21 is the inside wooden roof sheathing. 22 is the vertical side sheathing of the car, the upper edge of which is flush with the upper surface of the adjacent side plate. 23 is the longitudinally extending side fascia, the upper edge of which is flush with the upper surface of the top edge of the side sheathing 22. The outer edge of the roof sheathing 21 extends over the top edge of the side sheathing and terminates at the inner surface of the side fascia.

The eaves edges of the roof sheathing 21 are gained out at 24 to receive a longitudinally extending metallic flashing 25 whose inner edge terminates in an upwardly projecting open return bend hook 26 whose upper surface is below the plane of the top of the ungained roof sheathing and the flashing is flanged downwardly at 27 to enclose the outer edges 28 of the roof sheathing and then is bent outwardly at 29 over the top surface of the side fascia where it terminates in a depending flange 30 secured to the outer side of the side fascia.

Roof sheets 31 are disposed on opposite sides of the ridge 32 of the roof, said roof sheets having inverted U-shaped ridge flanges 32' lapped one over the other and side flanges 33, said side flanges 33 consisting of an upwardly extending inwardly inclined portion 34 terminating in a downwardly extending portion 35 spaced from the portion 34 and the main body 36 of the roof sheet.

The side flanges terminate at a point 37

short of the eaves edge of the roof and the unflanged portion of the eaves end side edge of the roof sheets are extended to form extensions or ears 38, and at the ridge corners 3 a portion of the ridge flanging and side flanging are cut away at 65 and the remaining portion of the ridge flanging is folded back on the portion of the side flanging as indicated at 66. The eaves edges of the 10 roof sheets are flanged downwardly at 39 and terminate in an outwardly pressed longitudinally extending rigidifying bead 40 that is arranged over and spaced from the outwardly extending portions 29 of the 15 flashing. The ears 38, flanges 39 and bead 40 of adjacent roof sheets are lapped one over the other at 41. Roof anchors 42 are provided, in the present instance, secured on the flashing at the eaves edge of the car, 20 one between the sides of two adjacent roof sheets. These anchors consist of a curved top 43, bent inwardly at each side at 44 to provide holding down portions, and the portions 44 are bent downwardly to provide 25 two vertical side portions 45 in contact with each other. The portions 45 are bent outwardly at 46 to provide roof sheet bearings that support the eaves edge of the roof sheets to limit rubbing of the flashing and 30 the roof sheets, and these portions are pressed downwardly at 47 to form seats 48 having apertures 49 through which nails or other fastening devices 50 may pass to secure the anchors in place. A portion of the 35 top 43 and the vertical portions 45 are cut away at 51 and a portion of the lower part of the contacting side vertical portions 45 are cut away to provide a slot 52 into which the lapped ears 28 extend and are loosely 40 confined as indicated at 53 so that the roof sheets may have room to move accordingly as the car moves and weaves.

Side seam caps 54 extend from ridge to eaves, said caps being of tubular form and having curved sides 55 inwardly turned at their lower ends and terminating in upwardly extending flanges 56 spaced from each other and from the sides 55 and when assembled on the car the flanges 56 are arranged in the spaces provided between the portions 34 and 35 of the side flanges 23 of the adjacent roof sheets. These side seam caps enclose the sides of adjacent roof sheets and the anchor therebetween at the eaves edge of the roof. The eaves end of the side seam caps are closed by bending the top down at 57 and the portion 57 is bent inwardly at 58 and the sides are then bent laterally at 59 over the portion 57, as indicated in Figs. 4 and 9. The ridge ends 60 of the side seam caps are lapped one over the other and are capped by the corner end of the ridge cap 60'.

A running board saddle 61 is positioned 65 over the side seam caps, said saddle support-

ing the usual running boards 62. To secure these parts in position a bolt 63 passes through apertures in the saddle 61, inverted U-shaped ridge cap 60', lapped ridge ends 60 of the side seam caps, roof sheathing 21, 70 and ridge pole 64.

To assemble the roof on a car, the anchors are secured over the flashing at proper distances, then the roof sheets are slid onto the roof towards the ridge so that the side flanges of the roof sheets engage the holding down portions 44 of the anchors as shown in Fig. 6, and the ridge end flanges are lapped one over the other. Then the side seam caps are slid toward the ridge onto the roof sheet side flanges and then the ridge caps are arranged over the ridge flanges of the roof sheets and the lapped ridge ends of the side seam caps. The running board saddle is then positioned over the side seam caps and the bolt 63 inserted as above described. At each end of the car a mullion is provided which is capped by a mullion cap 65' having a depending flange 66' secured to the end of the car and having side flanging 67 similar to the flanges of the side seam caps and at the eaves is flanged at 68 similarly to the depending eaves flanges of the roof sheets.

The invention as hereinabove set forth is embodied in a particular form of construction but may be variously embodied within the scope of the claims hereinafter made.

I claim:

1. In a car roof, in combination: roof sheathing, a flashing secured on said sheathing; roof sheets having side flanges, said flanges extending from the ridge of the roof to a point short of the eaves edge thereof and the unflanged portions of each sheet being extended to form ears, the ears of adjacent sheets being lapped one over the other; seam caps enclosing the side flanges of adjacent roof sheets, and an anchor at each eaves end of the seam caps, said anchors being secured on the flashing and enclosed by the seam caps, said anchors comprising a curved top bent inwardly at each side to provide a holding down portion engaging the upper portion of the side flanges of adjacent roof sheets, said top being bent to provide two depending contacting substantially vertical sides having a slot at their lower portions towards the eaves end into which the lapped ears of adjacent roof sheets extend, said sides terminating in outwardly extending bearing portions upon which the lapped ears bear, said bearing portions terminating in depressed seats that are secured to the car.

2. In a car roof, in combination: roof sheathing, a portion of said roof sheathing being gained out at each eaves edge; a flashing secured on said gained out sheathing; roof sheets disposed on opposite sides of the

ridge, said roof sheets having side flanges, said side flanges extending from the ridge to a point short of the eaves and the unflanged portions of said sides of the roof sheets extending outwardly forming extensions of said sheets, the eaves edges of said roof sheets terminating in flanges depending over the edge of the roof sheathing, said flanges having a longitudinally extending outwardly pressed rigidifying bead, the extensions of adjacent roof sheets being lapped, anchors secured at the eaves edges of the roof sheathing at the sides of adjacent roof sheets, said anchors having a top web and depending sides, said sides terminating in outwardly extending flanges, the lower portions of said sides having slots therein in which the extensions of said roof sheets are arranged, and seam caps enclosing the sides of said roof sheets and the anchors therebetween.

3. In a car roof, in combination: roof sheathing, flashing strips arranged thereon, roof sheets disposed on opposite sides of the ridge of the roof, anchors arranged on the flashing between the sides of adjacent roof sheets, seam caps enclosing the sides of adjacent roof sheets, said roof sheets having extensions on each side engaging said anchor.

4. In a car roof, in combination: roof sheets disposed on opposite sides of the ridge of the roof, an anchor arranged between adjacent sheets, portions of said roof sheets intersecting said anchors and seam caps enclosing the sides of adjacent roof sheets.

5. In a car roof, in combination: roof sheets disposed on opposite sides of the ridge of the roof, an anchor arranged between adjacent sheets, portions of said roof sheets intersecting said anchors and seam caps enclosing the sides of adjacent roof sheets and the anchor therebetween.

6. In a car roof, in combination: roof sheets, an anchor between adjacent roof sheets, each of said anchors having a slot therein, said roof sheets having a portion engaging in the slot of an adjacent anchor.

7. In a car roof, in combination: roof sheathing, flashing strips arranged thereon; roof sheets disposed on opposite sides of the ridge, said roof sheets having side flanges, said side flanges extending from the ridge to a point short of the eaves and the unflanged portions of said sheets forming extensions thereof, the eaves edges of said roof sheets terminating in flanges depending over the edge of the roof, an anchor arranged between adjacent roof sheets at the eaves of the car, said anchors having slots therein into which the extensions of the roof sheets extend and seam caps enclosing the side edges of adjacent roof sheets.

8. In a car roof, in combination: roof sheathing, flashing strips arranged thereon;

roof sheets disposed on opposite sides of the ridge, said roof sheets having side flanges, said side flanges extending from the ridge to a point short of the eaves and the unflanged portions of said sheets forming extensions thereof, the eaves edges of said roof sheets terminating in flanges depending over the edge of the roof, said depending flanges having an outwardly pressed rigidifying bead therein and the flanges of adjacent roof sheets being lapped, an anchor arranged between adjacent roof sheets at the eaves of the car, said anchors having slots therein into which the extensions of the roof sheets extend and seam caps enclosing the side edges of adjacent roof sheets.

9. In a car roof, in combination: roof sheathing; a portion of said roof sheathing being gained out at each eaves edge, a flashing secured on said gained out sheathing; roof sheets disposed on opposite sides of the ridge, said roof sheets having side flanges extending from the ridge to a point short of the eaves edge of the roof, and the unflanged portions of said roof sheets forming extensions thereof, the eaves edges of said roof sheets terminating in flanges depending over the edge of the roof, said flanges having a longitudinal stiffening bead formed therein, anchors secured at the eaves edges of said roof sheathing and at the sides of adjacent roof sheets, seam caps enclosing the side flanges of adjacent roof sheets and the anchor therebetween, said anchor engaging the roof sheets to hold them down on the roof independently of said seam caps.

10. In a car roof, in combination: roof sheathing; roof sheets disposed on opposite sides of the ridge, said roof sheets having side flanges extending from the ridge to a point short of the eaves edge of the roof and the unflanged portions of said roof sheets forming extensions thereof, anchors secured adjacent the eaves edges of said roof sheathing and at the sides of adjacent roof sheets, seam caps enclosing the side flanges of adjacent roof sheets and the anchor therebetween, said anchor engaging the roof sheets to hold them down on the roof independently of said seam caps.

11. In a car roof, in combination: roof sheathing; a portion of said roof sheathing being gained out at each eaves edge, a flashing secured on said gained out sheathing, roof sheets disposed on opposite sides of the ridge, said roof sheets having side flanges extending from the ridge to a point short of the eaves edge of the roof, and the unflanged portions of said roof sheets forming extensions thereof, the eaves edges of said roof sheets terminating in flanges depending over the edge of the roof, said flanges having a longitudinal stiffening bead formed therein, anchors positioned at the eaves edges of said roof sheathing and at the sides of ad-

5 adjacent roof sheets, seam caps enclosing the side flanges of adjacent roof sheets and the anchor therebetween, said anchor engaging the roof sheets to hold them down on the roof.

12. In a car roof, in combination; roof sheathing, roof sheets disposed on opposite sides of the ridge, said roof sheets having side flanges extending from the ridge to a point short of the eaves edge of the roof and the unflanged portions of said roof sheets forming extensions thereof, the eaves edges of said roof sheets terminating in flanges, anchors positioned at the eaves edges of said roof sheathing and at the sides of adjacent roof sheets, seam caps enclosing the side flanges of adjacent roof sheets and the anchor therebetween, said anchor engaging the roof sheets to hold them down on the roof.

13. In a car roof, in combination: roof sheathing, a flashing secured on each eaves edge thereof, roof sheets disposed on opposite sides of the ridge, said roof sheets each having a ridge flange and side flanges extending from the ridge to a point short of the eaves edge of the roof, the unflanged portions of the sides of the roof sheets forming extensions thereof, the eaves edge of the roof terminating in depending rigidified flanges spaced from the flashing, anchors positioned at the eaves edges of the roof between the sides of adjacent roof sheets, said anchors each having an upper holding portion arranged over the upper portion of the side flanges of adjacent roof sheets, and an extended portion arranged over the extensions of the roof sheets and side seam caps loosely engaging and enclosing the side flanges of adjacent roof sheets and enclosing the anchor therebetween.

14. In a car roof, in combination: roof

sheathing, roof sheets thereon disposed on opposite sides of the ridge, said roof sheets having a ridge flange and side flanges, the 45 sides of said roof sheets having extensions, the eaves edges of said roof sheets being flanged, anchors positioned between the sides of adjacent roof sheets, said anchors having a portion extending over the extensions of 50 the adjacent roof sheets and side seam caps enclosing the side flanges of adjacent roof sheets and the anchor therebetween.

15. An anchor for use in car roof construction comprising: a curved top bent inwardly at the sides of the top, and the inwardly bent portions being bent downwardly, the downwardly bent portions making contact with each other and being bent outwardly to provide bearings and the bearing portions being bent to form portions in a lower plane to provide a securing portion, a portion of said downwardly bent portions having a slot therein. 55 60

16. An anchor for use in car roof construction comprising: a top and two sides, said sides being formed with a cut out portion adapted to receive portions of adjacent roof sheets with which the anchor cooperates, said sides being bent at their lower ends to provide a bearing and a securing portion at a different elevation from the bearing. 65 70

17. An anchor for use in car roof construction comprising: a curved top portion, a base portion and an intermediate connecting portion provided with a slot adjacent its lower edge, said slot being adapted to receive portions of adjacent roof sheets with which the anchor cooperates. 75 80

In testimony whereof I have hereunto set my hand.

WILLIAM WRIGHT.
